EXPANSION DEVICE

Alfons Langecker, Stuttgart-Munster, Germany,
assignor to Robert Bosch Gesellschaft mit
beschränkter Haftung, Stuttgart, Germany

Application May 21, 1937, Serial No. 144,102
In Germany June 26, 1936

5 Claims. (Cl. 62—116)

The invention relates to a controlling valve by which the refrigerant liquified under pressure is relieved from pressure so that it can evaporate in the evaporator of the refrigerating apparatus at a temperature suitable for the absorption of heat. This valve is preferably arranged in the refrigerating chamber in proximity to the evaporator, as otherwise an evaporation would take place in the refrigerant pipe leading to the evaporator and heat would be abstracted from the surroundings. In the known valves of this kind it was necessary to arrange also the adjusting device serving for the control of the valve close to the evaporator. The space available for the accommodation of the goods to be cooled was thereby reduced; and furthermore, special precautions had to be taken to avoid the adjusting devices freezing up. In order to meet this drawback, the relief-valve was also frequently arranged outside the refrigerating chamber; in this case, either the reduction of the refrigerating efficiency due to the evaporation of the refrigerant in the feed pipe and the formation of hoar frost on this pipe thereby occurring had to be put up with, or this pipe had to be provided with heat insulation, which caused an additional consumption of material and increased costs of construction. In a known construction, the undesired evaporation of the refrigerant in this pipe was obviated by an excess pressure valve, arranged behind the relief-valve situated outside the refrigerating chamber, namely in proximity to the evaporator. This valve was to increase the pressure in the feed pipe to such an extent that no evaporation that detrimentally affected the refrigerating efficiency could take place and thus also no formation of hoar frost on this pipe. In order to save this additional valve, in another known construction the adjusting member was arranged, at least partly within the insulating wall of the refrigerator cabinet, and connected to the valve situated close to the evaporator by a long valve spindle. This arrangement presupposes very definite constructional conditions and the refrigerating plant can in this case only be connected to the refrigerating cabinet in the manufacturer's workshop, and both parts can only be despatched together as a unit. The refrigerating plant can thus not be subsequently combined with the cabinet and removed therefrom for the purpose of making repairs.

The invention enables the adjusting device to be left outside the refrigerating chamber, for instance in direct proximity to the condenser, so

that the refrigerant cannot evaporate in the feed pipe, without such constructional limitations as affect the form of the refrigerating device. This is attained by the valve member arranged in the refrigerating chamber close to the evaporator being connected, according to the invention, to the adjusting member situated outside the refrigerating chamber by a remote-control device, which is carried round the boundary edges of the substantially unpierced partition wall situated between the refrigerating chamber and the machine chamber. As a remote-control member, a flexible pull-and-push member, guided in a narrow tube, but comparatively rigid in the axial direction, or so-called Bowden wire, can preferably be used, the guide tube of which can serve at the same time for the conveyance of the refrigerant to the valve. As in the arrangement, according to the invention, care is certainly taken that the refrigerant cannot evaporate in the feed pipe, this pipe need not be provided with heat insulation, and the whole plant can therefore be easily inserted subsequently in the refrigerator cabinet, and in case of need removed therefrom.

Two examples of construction of the invention are shown in the accompanying drawing, in which—

Figure 1 shows a refrigerating plant for a domestic refrigerator cabinet having a remote-controlled controlling valve according to the invention.

Figure 2 shows in section and on an enlarged scale, an example of construction of the controlling device shown in Figure 1 and the corresponding adjusting device.

Figure 3 shows another construction of the float-controlled valve.

Figure 4 shows on a larger scale the valve member used in the construction shown in Figure 3, and,

Figure 5 shows an auxiliary device to facilitate the screwing off of the valve.

The refrigerating plant shown in Fig. 1 consists essentially of the motor compressor 10, the liquefier 11, and the evaporator 12. To the latter a collecting vessel 13 is connected, which communicates by a suction pipe 14 with the suction side of the motor compressor. In the piping 15, 25 leading from the liquefier to the evaporator a float container 16 is intercalated, which like the motor compressor 10 and a fan 17 serving for the conveyance of the cold air from the liquefier, is arranged on a supporting frame 18, mounted by means of elastic rubber cushions 19 on the cover 20 of a refrigerating chamber 21.

As Figure 2 shows, a float 24 is arranged in the float casing 16 which is provided with a pipe-connection 22, and to the float a lever 23 pivotally mounted on the bottom 26 of the casing 5 is connected. To this lever is attached the one end of a wire cable 21 guided in the tube 25, this cable being substantially rigid in the longitudinal direction but easily flexible transversely to its axis, so that a needle-valve 30 connected 10 to its other end and movably mounted in a casing 28 can easily follow the movements of the float, even when the part 25 of the pipe for the refrigerant serving for the guidance of the wire cable is bent several times in fitting the refrigerating plant in the refrigerator cabinet. 15

The whole refrigerating plant can thus, as shown in Figure 1, be arranged on both sides of the unpierced partition wall, so that the valve casing 28 remains in proximity to the evaporator 20 12, that is, in the refrigerating chamber 21, while the float container 16 is arranged outside the refrigerating chamber. The remote transmission means, formed by the refrigerant pipe 25 and the wire cable 21, may like the suction pipe 25 14, be so curved, when fitting that the plant put together in the workshop, filled with refrigerant and oil, and tightly closed, can be adapted to the most varied constructional conditions. The pipes 14 and 25 are led to the front end face of the 30 partition wall 20 and laid in a comparatively shallow and narrow groove 31' provided in this face, which, if necessary, can also be perfectly tightly closed by fibrous material or other loose packing medium. The end face is covered at the 35 front by a covering strip 32'. The free cross section between the container 16 and the float 24 is comparatively narrow, so that even slight fluctuations in the amount of refrigerant in the container cause great alterations in the level of the 40 liquid, and thus also can produce great adjusting movements and forces. In this way, the play, never quite avoidable in such a so-called Bowden wire, can be compensated for, and thus a working 45 of the valve 30 that corresponds to all practical requirements is obtained. In case, more especially in large refrigerating plants, the internal cross section of the guide-tube 25 left free by the wire cable 21 should not permit a sufficient passage for the refrigerant, a special 50 refrigerant pipe of larger cross section can be arranged between the float container 16 and the valve casing 28, in the inside of which the guide-tube 25 is preferably placed. The cable 21 in this tube is preferably formed by a closed wire 55 helix, whose coils wound with a comparatively small pitch enclose a bundle of thin wires, which are not, or only slightly twisted. It has been found that such a transmission member can be moved in its guide-tube without substantial 60 frictional losses even when it has curves of comparatively small diameter.

Of course, the valve 30 and the float 24 may be connected, if desired, by any other known remote control device. Instead of the float any other 65 adjusting device, for instance a diaphragm influenced by the pressure in the suction pipe, or another adjusting member customary in combination with a relief-valve, may, if required, be utilized for operating the valve 30.

70 In the example of construction shown in Figs. 3 and 4, a holder 32, provided with a collar part 31, is connected to the wire cable 21 connected by a lever 23 to the float 24, and guided in a narrow feed pipe 25, the holder being loaded by 75 a spring 33 bearing against the inner end wall

of the casing 28. A valve-seat 38 combined with a guide 37 to form one constructional unit is tightly inserted against a shoulder 40 in the casing 28 by means of a thread 41, which serves at the same time for securing a closure member 42 connected to a refrigerant pipe 12. The valve member 30 is provided with a thread 34 and with a constriction 35 which is somewhat longer than the collar part 31 of the holder and the internal thread 36 therein. At the constriction 35 the 10 diameter of the valve member is somewhat smaller than the diameter of the threaded portion 34 so that when the parts are in the position shown in Fig. 4, the valve member 30 is loosely fitted in or connected to the collar part 31 of the holder 32. The valve member can thus place itself obliquely relative to the holder to a trifling extent. The advantage is thereby obtained that no frictional forces that prejudicially effect the 15 easy movability of the valve can occur in the valve-guide 37 if there is a transverse strain in the wire cable 21, or if in the fixing of the holder 32 to the wire cable 21, or in the insertion of the valve seat 28 provided with the guide 27, these 20 parts should not lie exactly co-axial in the centre line of the valve. The play necessary for this purpose between the constriction and the internal thread of the part 31 amounts only to about 0.1 mm. and thus practically does not at 25 all affect the exactitude of control.

The clamping sleeve 42 shown in Fig. 5 may be employed for the insertion and screwing out of the valve member. This sleeve has two approximately semicircular tongues 44, divided by slots 43, and which are somewhat externally expanded. The tongues can be clamped on the valve member by pushing a clamping ring 45 over two externally projecting recesses 46 in the wall of the sleeve.

The constriction between the thread and the 40 shaft used in this construction may also be employed with advantage in other valves in order to avoid a jamming of the valve member in its guide.

I declare that what I claim is:

1. A refrigerator comprising a refrigerating chamber having a substantially unpierced wall situated between the heat absorbing and heat delivery parts of the refrigerator, a compressor, a liquefier connected to said compressor, an evaporator in said refrigerating chamber, conduit means connecting one end of said evaporator to said compressor and the other end to said liquefier, a portion of said conduit means extending around the boundary edge of said wall, a valve member arranged in said conduit means between said liquefier and said evaporator and in the refrigerating chamber, in proximity to said evaporator, a control member arranged in said conduit means outside of said refrigerating chamber, and a remote control device operated by said control member to actuate said valve member, said remote control device extending around the boundary edges of said wall. 45

2. A refrigerator comprising a refrigerating chamber having a substantially unpierced wall situated between the heat absorbing and heat delivery parts of the refrigerator, a compressor, a liquefier connected to said compressor, an evaporator in said refrigerating chamber, conduit means connecting one end of said evaporator to said compressor and the other end to said liquefier, a portion of said conduit means extending around the boundary edge of said wall, a valve member arranged in said conduit means between 50 said liquefier and said evaporator and in the refrigerating chamber, in proximity to said evaporator, a control member arranged in said conduit means outside of said refrigerating chamber, and a remote control device operated by said control member to actuate said valve member, said remote control device extending around the boundary edges of said wall. 65

5 said liquefier and said evaporator and in the refrigerating chamber, in proximity to said evaporator, a control member arranged in said conduit means outside of said refrigerating chamber, and a Bowden wire extending around the boundary edge of said wall and connecting said control member and said valve member.

10 3. A refrigerator comprising a refrigerating chamber having a substantially unpierced wall situated between the heat absorbing and heat delivery parts of the refrigerator, a motor compressor, a liquefier connected to said compressor, an evaporator in said refrigerating chamber, conduit means connecting one end of said evaporator to said compressor and the other end to said liquefier, a portion of said conduit means extending around the boundary edge of said wall, a control member arranged in said conduit means outside of said refrigerating chamber, a valve member arranged in said conduit means between said liquefier and said evaporator and in the refrigerating chamber in proximity to said evaporator, and a Bowden wire arranged in said conduit means and operated by said control member to actuate said valve member.

15 4. A refrigerator comprising a refrigerating chamber having a substantially unpierced wall situated between the heat absorbing and heat delivery parts of the refrigerator, a motor compressor, a liquefier connected to said compressor, an evaporator in said refrigerating chamber, conduit means connecting one end of said evaporator to said compressor and the other end to said liquefier, a portion of said conduit means extending around the boundary edge of said wall, a valve casing arranged in said conduit means be-

20 tween said liquefier and said evaporator and in the refrigerating chamber in proximity to said evaporator, a movable valve member in said casing, said member having a valve portion at one end, a threaded portion at the other end and a 5 constricted portion intermediate said ends, a holder for mounting said valve member and provided with a threaded hole through which the threaded portion of said valve member is screwed so that said constricted portion is loosely mounted in said hole, a control member outside of said refrigerating chamber, and a remote control device operated by said control member to actuate said holder and said valve member, said remote control device extending around the boundary 10 edges of said wall.

25 5. A refrigerator comprising a refrigerating chamber having a substantially imperforate wall between the heat absorbing and heat delivery parts of said refrigerator, a compressor, a liquefier connected to said compressor, an evaporator in said refrigerating chamber, conduit means connecting one end of said evaporator to said compressor and the other end to said liquefier, a portion of said conduit means extending around the boundary edge of said wall, a valve member arranged in said conduit means between said liquefier and said evaporator and in the refrigerating chamber in proximity to said evaporator, a control member arranged in said conduit means 20 outside of said refrigerating chamber, and a remote control device arranged in said conduit and operated by said control member to actuate said valve member.
